Primary Examiner — Susan Moon Lee(74) *Attorney, Agent, or Firm* — Davis Graham & Stubbs LLP(57) **CLAIM**

I claim the ornamental design for a pet dish, as shown and described.

DESCRIPTION

FIG. 1 is a top perspective view of a pet dish in accordance with the present invention;

FIG. 2 is a bottom perspective view of the pet dish of FIG. 1;

FIG. 3 is a top elevational view of the pet dish of FIG. 1; FIG. 4 is a front elevational view of the pet dish of FIG. 1, the back, left side, and right side elevational views are identical to the front elevational view; and,

FIG. 5 is a bottom elevational view of the pet dish of FIG. 1.
